Howard C. Thompson
ATTORNEY

UNITED STATES PATENT OFFICE

JOSEPH SOSS, OF BROOKLYN, NEW YORK

HINGE

Application filed September 20, 1927. Serial No. 220,676.

This invention relates to what are known as concealed hinges wherein the knuckle or hinge joint is concealed or partially concealed by a hood portion encircling the pintle bearing portion of the hinge; and the object of the invention is to provide a hinge of the class specified, which is fashioned from sheet metal into an elongated butt body having a multiplicity of knuckles or pintle bearing members arranged longitudinally thereof whereby a large number of bearings is provided for the hinge to permit of the construction of the separate butts of comparatively thin sheet metal, and yet produce the required strength, rigidity and durability in the several uses of the hinge and particularly in its use in hanging motor vehicle doors; a further object being to provide a hinge, one of the butts of which is fashioned from two sheet metal bodies, one of said bodies being fashioned substantially centrally thereof to form a plurality of cylindrical pintle bearings or knuckles and the other body of which encircles said knuckles to form a hood covering for the joint of the hinge and also to reinforce and strengthen the hinge, said bodies being secured together by riveting, welding or in any other desired manner; a further object being to fashion the attaching plate portion of the butt in such manner as to conform with the contour of the door or door frame in connection with which the hinge is employed, and especially when the door and door frame are of a curved contour; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side view of a hinge made according to my invention with part of the construction broken away and in section.

Fig. 2 is a section on the line 2—2 of Fig. 1.

Fig. 3 is a sectional, detail view of one part or body employed in the formation of one of my improved hinge butts.

Fig. 3^a is a view looking in the direction of the arrow 3^a of Fig. 3.

Fig. 4 is a view similar to Fig. 3 but showing the other part or body; and,

Fig. 5 is a perspective and sectional view of the part shown in Fig. 3 of the drawing, in a modified form of construction.

In the drawing, 10 represents one butt or part of my improved hinge, and 11 the other butt thereof, the butt 10 being formed from a single sheet of metal folded centrally to form a plurality of substantially cylindrical 65 pintle bearings or knuckles 12, the side portions of the sheet being brought together and secured by riveting, welding or otherwise to form an attaching plate portion 13. The sheet is cut out at spaced intervals to 70 form recesses 14 intermediate the cylindrical bearings or knuckles 12 to receive the knuckles or bearings of the other butt 11 of the hinge.

The butt 11 is composed of two sheet metal 75 bodies or parts 11^a and 11^b shown in detail in Figs. 3 and 4 of the drawing. The part 11^a is formed from a comparatively thin sheet of metal, the central portion of which is fashioned to form a plurality of cylindrical bearings 15 between which are recesses 16 to receive the knuckles 12 of the butt 10. The part 11^b is fashioned at one end to form a curved hood portion 17 which is adapted to encircle the knuckles 15 of the part 11^a. The free 85 edge of the hood portion 17 is provided at spaced intervals with inwardly turned flanges 18 folded upon the inner face of the hood 17 and which are of a length equal to the length of the bearings 15 and upon which said bearings rest and bear. Between the flanges 18 are spaces 19 providing for the free action of the bearings 12 of the butt 10. If desired, the diameters of the latter bearings may be slightly greater than that of the bearings 15. The 90 recesses 19 formed by the flanges 18 prevent the marring of the surfaces of the bearings 12 in the operation and use of the hinge. The flanges 18 also serve to reinforce and strengthen the hood portion 17 as well as the pintle 95

100

bearing portion of the butt 11 as a whole. The separate parts 11^a and 11^b may be secured together by riveting, welding or in any other desired manner to form a unit body or structure thereof, and when so made, will produce a butt of great strength and durability. The shank portion of the part 11^b extends onto the shank portion of the part 11^a to form the attaching plate portion of the butt.

In the construction shown, in adapting a hinge for the mounting of motor vehicle doors, the shank of the butt 11 and its separate parts are offset at right angles as seen at 20, Fig. 2 of the drawing. This offset portion is curved from the central portion of the hinge, with respect to its length, to the opposite ends thereof as seen in Fig. 1 of the drawing. The free edge 21 of the plate is also correspondingly curved and the attaching plate proper 22 extends at right angles to the offset part 20 and in parallel relation to the shank, extending from the knuckle of the hinge, and is apertured for attachment to the door frame, it being understood that the butt 10 is secured to the door in the construction shown.

It will be understood that my invention is not necessarily limited to any particular shape or contour of the attaching plate portion of the respective butts, as said attaching plates may be fashioned to suit a door frame and door of any desired construction.

In Fig. 5 of the drawing, I have shown a slight modification of the part 11^b of the butt 11 wherein the hood portion 17 is pressed or stamped from the sheet of metal, rather than folded and turned as in Fig. 3 to form end wall members 23 of the material of the part 11^b which operate to close the ends of the hinge and are provided with pintle pin apertures 24, it being understood that the butt parts 10 and 11 are coupled together by a pin 25 passed through the knuckles or bearings 12 and 15 respectively. As seen in Fig. 1 of the drawing, the pin 25 may be provided with a large head 26 at its upper end to act as a cover, overlying the upper edges of the butt parts 10 and 11.

In producing my improved hinge, and after the parts or butts 10 and 11 have been coupled together by the pin 25, the bearings 15 may be firmly crimped or compressed upon the pin 25 to compact the metal of the butt 11 on said pin, forming secure and firm coupling between said parts, whereas the bearings 12 are free to rotate on the pin 25 and will produce a multiplicity of independent bearings on said pin governed by the number of bearings 12 employed and also the length of the hinge.

With my improved construction, I have simplified the manufacture of hinge butts and reduced the cost thereof by virtue of the thickness of the material employed and the simplicity in the formation of the separate parts

of the butt, and have further effected a material saving in labor, required in hanging a door in connection with a door frame and provided for the proper swinging and mounting of the door in the frame. At the same time, I have provided what is known as a covered joint hinge wherein the pintle bearings or knuckles are concealed and protected by a hood member, which produces a neat and finished appearance and also protects the joint of the hinge from exposure to the elements. While I have shown certain details of construction for carrying my invention into effect, it will be understood that I am not necessarily limited to these details, and various changes therein and modifications thereof may be made within the scope of the appended claims without departing from the spirit of my invention or sacrificing its advantages.

It will be understood that the separate parts of the butts may be constructed of sheet metal of any desired thickness, and the thickness of the sheets in the comparative parts may vary, if desired. It will also be understood that the separate parts or sections of the butts may be secured together by riveting, or welding at any desired points to give the required strength and rigidity to the butt and in retaining the parts or sections thereof together in the operation of forming the same, and after the same have been given the desired shape or contour. It will also be understood that each butt part of my improved hinge may include one pintle bearing or knuckle, and one recess, or a multiplicity of said knuckles and recesses.

Further, my invention is not limited to the securing of the pintle pin to the knuckles or bearings of one of the butt parts, as the pin may be detachably supported in connection with the knuckles of both parts as in other hinges of this type. As to the use of my improved hinge, it will be understood that the same may be applied to apparatus or doors and swinging members of any kind or class. The disclosure herein made is merely for the purpose of illustrating one method of carrying my invention into effect.

Having fully described my invention, what I claim as new and desire to secure by Letters Patent, is:—

1. In a hinge, one of the butts of which is fashioned from two sheet metal bodies, one of said bodies being fashioned to form a plurality of cylindrical pintle bearings spaced longitudinally of one end thereof, the other body being fashioned to form a curved hood portion substantially encircling said pintle bearings to form of said bodies when secured together, a butt having a curved hood portion with bearings spaced longitudinally of the hood portion and recesses intermediate said bearings to receive the pintle bearings of the other butt of the hinge, means on said hood portion interposed between the same and the

pintle bearings of said butt to offset the same with reference to said hood portion and to reinforce and strengthen the hood portion and said bearings, said means comprising flanges at the free edge of the hood portion and turned inwardly upon the inner face of said hood portion, both bodies of the butt extending to form an attaching plate portion, said attaching plate portion being offset with respect to the shank, and part of said offset portion being curved in the longitudinal plane of the butt.

2. In a covered joint hinge of the class described, one of the butts of which is composed of two comparatively thin inner and outer sheet metal hinge parts, the sheet of the inner part being fashioned to form a cylindrical bearing with a recess at one side of said bearing, the sheet of the outer part being fashioned to form a curved hood conforming with the general contour of and partially encircling the bearing of the inner part to form a continuous cover member for the joint of the butt, and a curved plate arranged on the inner face of said hood and between it and said bearing to reinforce the hood and to offset the bearing with respect to the hood to provide a recess in the hood to freely receive the pintle bearing of the other butt of the hinge.

3. In a covered joint hinge, one of the butts of which is fashioned from two sheet metal hinge bodies, one of said bodies having a plurality of cylindrical pintle bearings with recesses between said bearings for receiving the bearings of the other butt of the hinge, the other body having a curved hood portion substantially encircling the pintle bearings to form a cover for the joint of the hinge, the free edge of the curved hood portion including curved plates arranged upon the inner face and conforming with said hood portion and arranged between it and said bearings to reinforce the pintle of the hinge and to space the pintle bearings from said hood.

45. In testimony that I claim the foregoing as my invention I have signed my name this 15th day of Sept., 1927.

JOSEPH SOSS.
